ATTORNEY

WITNESS:

UNITED STATES PATENT OFFICE.

GEORGE H. MARTIN, OF WARM SPRINGS, MONTANA.

SPRING WHEEL.

Application filed May 1, 1926. Serial No. 106,067.

This invention relates to a spring wheel for motor vehicles and the like, the general object of the invention being to provide a floating casing which is attached to the hub 5 and a second casing which is designed to carry the tread part, with springs for resisting the movement of one casing in relation to the other, the springs being arranged within the casings so that they are protected from 10 the elements and dirt and dust.

Another object of the invention is to so arrange the parts that both the springs at the lower part of the wheels and the springs at the upper part of the wheel will be 15 brought into action simultaneously.

This invention also consists in certain other features of construction and in the combination and arrangement of the several parts, to be hereinafter fully described, illustrated in the accompanying drawings and specifically pointed out in the appended 20 claims.

In describing my invention in detail, reference will be had to the accompanying 25 drawings wherein like characters denote like or corresponding parts throughout the several views, and in which:—

Figure 1 is an elevation of the improved wheel, with parts broken away.

30 Figure 2 is a section on line 2—2 of Figure 1.

Figure 3 is a section on line 3—3 of Figure 1.

35 Figures 4 and 5 are views of the spring engaging studs.

In these views, 1 indicates the hub of the wheel which is provided with the flanges 2 and 3. A disk-like plate 4 is fastened to the flange 3 and said plate is formed with the 40 outer flange 5 and the inner flange 6. This flange 6 may be welded to the plate. A disk-like plate 7 is fastened to the flange 2 and engages the free edges of the flanges 5 and 6 so that the plates 4 and 7 and the 45 flange 5 forms a casing which is carried by the hub. The outer casing is formed of a ring shaped plate 8, the center hole in which is made considerably larger than the flange 3, and the cover plate 9 which abuts the 50 flange 10 of the plate 8. This cover plate is attached to the plate 8 by the bolts 11 and the ring shaped member 12 located within the inner casing and surrounding the hub is fastened to the outer casing by the bolts 13 55 which pass through large holes 14 in the plates 4 and 7 of the inner casing. This

member 12 is of channel shape in cross section, with the bolts 13 passing through its flanges. Transversely extending beads 15 are formed on the inner face of the flange 10 and similar beads 16 are formed on the outer face of the member 12. Studs 17 have their heads engaging the flanges 5 and 6 of the inner casing, with their square stems 18 passing through holes in said flanges, 60 each stem having a rounded recess 19 therein, the recesses in the stems of the outer set engaging the beads 15 on the flange 10, while the recesses of the inner set engage the beads 16 of the member 12. The under faces of 70 the heads of the outer row of studs are convex, as shown at 17' in Figure 5, while the under faces of the heads of the inner row of studs are concaved, as shown at 17'' in Figure 4. Thus these heads conform to the 75 surfaces of the flanges with which they engage. A coiled spring 20 is placed between each pair of studs, the ends of the springs engaging rounded projections 21 on the heads of the studs. 80

Ball bearings 22 are placed in depressions 23 formed in the parts 8 and 9 of the outer casing and engage parts of the inner casing and said parts 8 and 9 are provided with annular grooves 24 for receiving packing material 25 for preventing dirt from entering between the two casings. The projection forming the inner groove 25 is made large enough to carry the brake drum 26. 85

Any suitable form of tire or tread can be 90 carried by the flange 10 of the outer casing, Figure 2 showing an ordinary demountable rim 27 fastened thereon by the ring 28 which is bolted to the outer casing.

From the foregoing, it will be seen that 95 the inner casing floats with respect to the outer casing and that the member 12 is caused to move with the outer casing by being connected thereto by the bolts 13, these bolts passing through large holes in the 100 inner casing so as to not interfere with the relative movement of the casings. The inner casing is connected with the hub and carries the studs and springs, the springs acting to hold the studs against the inner and 105 outer parts of the outer casing. Thus the weight of the vehicle on the hub 1 will cause the inner casing to move downwardly in the outer casing, the outer casing being held against movement by resting on the 110 ground. Thus considering the following relative positions as momentary positions

the lower part of the inner casing moves away from the head of the lowest stud and the flange 6 pulls the lowest stud of the inner row downwardly with it, thus compressing the lowest spring. The flange 5 of the inner casing causes the top stud of the outer row to move downwardly but the companion stud of the inner row is held stationary by the member 12 so that the uppermost spring is also compressed and the two springs therefore resist the downward movement of the hub and the inner casing. Of course, the springs other than at the top and bottom of the device come into action and help the springs above mentioned to resist the movement of the parts.

In this manner, the springs act to absorb shocks incident to the travel of the vehicle and take the place of a pneumatic tire and as said springs are enclosed, they will last for a long time and there is but little danger of anything happening to the wheel as the trouble incident to the use of pneumatic tires is eliminated.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A spring wheel comprising a hub, an

inner casing carried thereby, an outer casing, the casings having relative movement circumferentially, a ring located within the inner casing, means for fastening the ring to the outer casing, an outer row of members movably carried by the inner casing and engaging the inner circumference of the outer casing, an inner row of movable members carried by the inner casing and engaging the outer circumference of the ring and a coiled spring arranged between each pair of members, said springs acting to resiliently space radially therefrom the respective flanges of the inner casing.

2. A spring wheel comprising a hub, an inner casing carried thereby, said casing having inner and outer flanges, an outer casing, the casings having relative movement circumferentially, a row of studs carried by the outer flange of the inner casing and engaging the inner circumference of the outer casing, an inner row of studs movably carried by the inner flange of the inner casing, a ring arranged within the space between the inner flange of the inner casing and the hub, means for connecting the ring with the outer casing, said ring engaging the inner row of studs and springs arranged between the studs of the inner and outer rows, said springs acting to resiliently space radially therefrom the respective flanges of the inner casing.

In testimony whereof I affix my signature.

GEORGE H. MARTIN.
